UNITED STATES PATENT OFFICE

PERRY R. CASSIDY, OF DARIEN, CONNECTICUT, ASSIGNOR TO THE BABCOCK & WILCOX COMPANY, OF BAYONNE, NEW JERSEY, A CORPORATION OF NEW JERSEY

WATER TUBE BOILER

Application filed January 25, 1928. Serial No. 249,260.

This invention relates to a water tube boiler having a plurality of cross steam and water drums and will be understood from the description in connection with the accompanying drawings in which Fig. 1 is a vertical section through an illustrative embodiment of the invention taken along the line 1—1 of Fig. 2, and Fig. 2 is a view at right angles to Fig. 1 partly in section along the line 2—2 of Fig. 1.

In the drawings, reference character 5 indicates a furnace above which is located a water tube boiler, the water tube boiler comprising a front steam and water drum 6 that extends crosswise of the boiler and a corresponding rear drum 7 connected by one or more rows of steam circulators 8 located inside of the boiler casing. One or more water circulators 9 may connect the water spaces of the drums, said water circulators being located outside of the boiler casing. Downtake headers 10 are connected to the rear drum 7 by means of the nipples 11. A bank of inclined tubes 12 connects the downtake headers 10 to the uptake headers 13 and nipples 14 connect the upper ends of the uptake headers 13 to the front drum 6. These nipples extend inside the drum preferably above the water level therein and terminate in bends 15 turned away from the side into which the steam circulators 8 enter. A feed water inlet pipe 16 is provided for the rear drum 7.

The drums 6 and 7 are preferably lined with tile on the furnace side and the hot products of combustion from the furnace pass in a single pass across the tubes 12 and thence out through the outlet 17 a portion of the same contacting with the tubes 8. Tubes 18 connect the steam space of the steam and water drum 7 to the superheater 19 across which the gases also pass in a single pass.

Downcomer tubes 20 connect the ends of the water space of the drums 6 to a distributor 21 on each side of the furnace. Tubes 22 connect the distributors 21 to lower headers 23 along opposite sides of the furnace. Tubes 24 connect the distributors 21 to opposite ends of lower cross headers 25 and 26 that may be spring supported. Rows of

tubes 27 and 28 lined with tile and bent to form an ash hopper, connect headers 25 and 26 to cross headers 29 and 30, respectively. A row 31 of front water wall tubes and a row 32 of rear water wall tubes connects the headers 29 and 30 to upper headers 33 and 34, respectively. Fuel burners 35 extend through the front wall of the furnace.

A row of side furnace wall tubes 36 on one side and a corresponding row 37 on the other side connect the lower headers 23 to upper headers 38. A group 36' of a few tubes at the front of each side wall connects the headers 23 to short upper headers 38' located short distances below the headers 38. Tubes 39 may be provided on the outside of the furnace between the headers 33 and 25 for local circulation. Tubes 40 between the headers 26 and 34, and tubes 41 between the headers 23 and 38, may be provided for the same purpose. A downcomer tube 42 may be provided on each side of the boiler from the water space of the steam and water drum 7 and is connected to the downcomer tube 20, if necessary, to provide sufficient water for the water wall tubes. When unnecessary, the valve in pipe 42 is closed. Risers 45 extend from the front cross header 33 to the steam and water drum 6 and enter the same at about a 45° angle from the bottom. Corresponding risers 46 extend from the rear cross header 34 to the drum 6. Risers 47 extend from the upper headers 38 to the drum 6 and risers 47' extend from the short upper headers 38' to the drum 6. Safety valve nozzles 48 are provided along the upper side of the drum 7.

The operation is as follows: Steam is generated in the inclined tubes 12 in the usual manner and the mixture of steam and water passes upwardly through the nipples 14 into the front drum 6 where separation takes place. The steam from the drum 6 passes with some entrained moisture through the tubes 8 into the drum 7 and the steam has its quality improved while passing through these tubes by means of the hot products of combustion, some of which contact with the tubes, so that the steam in the steam space of the drum 7 is relatively dry even before it

passes to the superheater 19. The main portion of the water for the tubes along the furnace walls passes downwardly through the tube 20 and in this way the water wall tubes receive water of about the same temperature as that in the steam generating portion of the boiler. The water entering the lower headers around the furnace walls passes upwardly and is partially vaporized, the mixture of steam and water passing into the front drum 6 after a partial separation in the upper headers 33, 34 and 38 that causes water to flow downwardly through the tubes 39, 40 and 41.

15 I claim:

1. In a water tube boiler and its furnace, a front cross steam and water drum, a rear cross steam and water drum, a bank of inclined water tubes and connections between the ends of said tubes and the respective steam and water drums, tubes communicating with the water spaces and the steam spaces, respectively, of said steam and water drums, said furnace having a wall provided with water tubes, and downcomers and risers both connected to said front drum and communicating with the respective ends of the furnace wall tubes.

2. In a water tube boiler and its furnace, a front cross steam and water drum, a rear cross steam and water drum, a bank of inclined water tubes and connections between the ends of said tubes and the respective steam and water drums, tubes communicating with the water spaces and the steam spaces, respectively, of said steam and water drums, said furnace having a wall provided with water tubes, downcomers and risers both connected to said front drum and communicating with the respective ends of the furnace wall tubes, and a steam outlet connected to the other drum.

3. In a water tube boiler and its furnace, a front cross steam and water drum, a rear cross steam and water drum, a bank of inclined water tubes and connections between the ends of said tubes and the respective steam and water drums, tubes communicating with the water spaces and the steam spaces, respectively, of said steam and water drums, said furnace having a wall provided with water tubes, downcomers and risers both connected to said front drum and communicating with the respective ends of the furnace wall tubes, and a feed water inlet and a steam outlet connected to the other drum.

4. In a water tube boiler and its furnace, a front cross steam and water drum, a rear cross steam and water drum, a bank of inclined water tubes and connections between the ends of said tubes and the respective steam and water drums, tubes communicating with the water spaces and the steam spaces, respectively, of said steam and water drums, said furnace having a wall provided with

water tubes of greater length than said inclined tubes, and down-comers and risers both connected to said front drum and communicating with the respective ends of the furnace wall tubes.

5. In a water tube boiler and its furnace, a front cross steam and water drum, a rear cross steam and water drum, a bank of inclined water tubes and connections between the ends of said tubes and the respective steam and water drums, tubes communicating with the water spaces and the steam spaces, respectively, of said steam and water drums, said furnace having a wall provided with water tubes, and upper and lower headers to which the respective ends of the wall tubes are connected, said headers being both connected to said front steam and water drum.
